US0D1089156S

(12) **United States Design Patent** (10) **Patent No.:** **US D1,089,156 S**
(45) **Date of Patent:** **** Aug. 19, 2025**

(54) **HEADSET**

(71) Applicant: **3M Innovative Properties Company**,
St. Paul, MN (US)

(72) Inventors: **William P. Atwood**, St. Paul, MN (US);
Antoine Bernier, Montréal (CA);
Bernard Daoust, Montréal (CA);
Katrin Braun, Montréal (CA)

(73) Assignee: **3M Innovative Properties Company**,
St. Paul, MN (US)

(**) Term: **15 Years**

(21) Appl. No.: **29/917,082**

(22) Filed: **Nov. 17, 2023**

Related U.S. Application Data

(62) Division of application No. 29/758,486, filed on Nov. 16, 2020, now Pat. No. Des. 1,010,607.

(51) **LOC (15) Cl.** **14-01**

(52) **U.S. Cl.**

USPC **D14/205**

(57) **CLAIM**

The ornamental design for a headset, as shown and described.

DESCRIPTION

FIG. 1 is a bottom left perspective view of a headset in accordance with an embodiment of the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dash-dash broken lines in the figures represent unclaimed subject matter and form no part of the claimed design.

1 Claim, 6 Drawing Sheets
